UNITED STATES PATENT OFFICE

WILLIAM FRIEDMAN, OF NEW YORK, N. Y.

TOILET ACCESSORY

Application filed June 25, 1931. Serial No. 546,825.

This invention relates to toilet accessories, and particularly to toilet accessories of the type adapted to contain and dispense powder.

The objects of the invention are to provide an improved toilet accessory of the character specified; to obtain a positive feeding of the powder; to prevent leakage of the powder while the device is being carried around, as in a lady's handbag; to provide for automatically opening and closing the dispensing orifice; to avoid compacting pressure upon the powder; to enable the container to be readily refilled; to retract the follower during the filling operation; to enable the follower to be retracted and released while the container is closed; to secure simplicity of construction and operation, and to obtain other advantages and results as may be brought out in the following description.

Referring to the accompanying drawing in which like numerals of reference indicate similar parts throughout the several views;

Figure 1 is a plan of a toilet accessory with the cover section open embodying my invention;

Figure 2 is a sectional view of a toilet accessory embodying the invention, and showing the same completely closed;

Figure 3 is a similar sectional view showing the parts in partly open position; and

Figure 4 is an underneath view of the dispensing member or plate.

Fig. 5 is a detail view showing the structure of the spring depressing means.

In the specific embodiment of the invention illustrated in said drawing, the reference numeral 1 indicates the body section of a toilet accessory to which is hinged, as at 2, a cover section 3. Within the body section is mounted a fitment comprising a container 4 to which is hinged an inner cover 5. The invention resides more particularly in the construction of the parts comprising this fitment.

Container 4 as herein constructed provides a bottom wall contiguous to the bottom wall of the body section, and provides a side or peripheral wall the upper part of which is spaced inwardly from the peripheral wall of the body section for reception of the mar-

gin of the inner cover. Opposite portions of the side wall are parallel and extend substantially to the bottom wall, so as to slidably receive a follower or false bottom 6 within the container. The peripheral edge 55 of the follower 6 fits against the side wall entirely around the container so that powder introduced upon the follower will remain thereon without passing to the under side thereof. A spring 7 is interposed between 60 the follower and the bottom wall for normally urging the follower upward.

Means may be provided for compressing the spring 7 at such times as it may be desired to fill the container. As one such means, I 65 have shown a compressor strip 8 one end of which normally lies between the spring and the follower, and the other end of which rests upon the bottom of the container. The strip is longitudinally slotted, and through 70 the slot, with an overlying head, is a stud 9 the lower end of which is carried by a slide or button on the exterior of the body member. The bottom walls of the body section and the container are slotted, and movement 75 of the stud in a direction toward the spring-engaging end of the strip will obtain a depression of the strip and a corresponding compression of the spring. Release of the spring is effected by sliding the button and 80 stud in the opposite direction.

The inner cover 5 preferably comprises a ferrule or collar 10, hinged for instance to the side wall of the fitment. This ferrule 10 is circular in configuration, and rotatably 85 carried thereby is a dispensing member or plate 11. This dispensing plate provides a peripheral groove into which the peripheral edge of the collar engages thereby securing an engagement permitting rotation of the 90 plate with the collar remaining stationary.

At the middle part of the dispensing member 11 is a dispensing orifice 12 from which powder is to be ejected for use as required. On the underside of the plate is provided 95 means for ejecting the powder from the orifice. As here shown, there are a pair of spiral ridges 13 provided on said plate, said ridges starting from adjacent the periphery of the member and curling inwardly toward the 100

orifice. With the powder pressed toward the dispensing plate, a rotation of the plate rotates the spiral ridge in contact with the powder, and thereby urges the powder toward the center, as a result of which the accumulation of powder will cause an ejection of powder from the orifice. Preferably the spring pressure against the follower is sufficient to obtain the desired contact of the powder for lateral feeding purposes, but avoids as far as possible a compacting of the powder as the feeding is more profuse and efficient with the least possible compacting.

In order to prevent leakage through the orifice at such time when powder is not desired, as when the device is being carried around, I provide a closure 14 here shown as a plate having somewhat the shape of a button leg, the large end having a diameter greater than the orifice and the smaller end having a downwardly directed fin 15 adapted to engage in the powder. The closure is pivoted, as by rivet 16 intermediate its ends to the under side of the dispensing plate in close association to the discharge orifice such that the larger part of closure may be swung into juxtaposition with the orifice and close the same. Projection of the fin downwardly into the powder will cause the closure to have a swinging action one way or the other as the dispensing member is rotated one way or the other. The parts are preferably so arranged that a clock-wise rotation of the dispensing member will tend to uncover the orifice whereas a counter-clockwise rotation will tend to swing the closure over the orifice. Preferably the spiral ridges 13 are so placed as to act as stops to limit the amplitude of swing for the closure to open and to closed position.

In use, the operator merely turns the dispensing member in a clockwise direction until sufficient powder has been ejected to meet the needs or wishes of the operator. The initial rotation of the member will not only obtain a swinging movement of the closure 14 from covering the orifices, but begins immediately to feed powder to the orifice, so that the moment the orifice is uncovered there will be a supply of powder ready for ejection, and the accumulated surplus is accordingly immediately ejected followed by a continued supply as long as the rotation of the member continues. When sufficient powder has been obtained, a slight counter-clockwise rotation of the member causes the closure to swing in an opposite direction and thereupon cover the orifice until more powder is desired. The dispensing member with the ferrule carrying the same, which parts constitute the inner cover, normally remain closed with respect to the container, but when it is desired to fill the container, said inner cover is readily swung upward as shown in Figure 3. Before opening the inner cover, the spring is com-

pressed to relieve the follower from its outward actuation. While I have shown the spring retaining means as manually operated and have shown the orifice closing means as automatically operated, either or both of these may be otherwise operated if so desired.

Obviously other detail changes and modifications may be made in the construction and use of my improved toilet accessory without departing from the spirit or scope of the invention, and I do not wish to be understood as limiting myself to the exact construction shown or described except as set forth in the following claims when construed in the light of the prior art.

Having thus described the invention, I claim:

1. A toilet accessory comprising a circular dispensing member having a discharge orifice at a middle part thereof, and means for feeding powder or the like lying contiguous to the member toward the middle part of said member and discharge the same from said orifice.

2. A toilet accessory comprising a dispensing member having a discharge orifice therein, and a spiral ridge on said member for feeding powder or the like toward said discharge orifice.

3. A toilet accessory comprising a fitment having a rotatable member, and a spiral ridge on said member for feeding powder or the like in a direction substantially parallel to the said member.

4. A toilet accessory comprising a dispensing member having a discharge orifice therein, means for holding powder or the like in engagement with said member, and means operated by rotation of said member in its own plane for feeding powder in engagement with said member toward said orifice.

5. A toilet accessory comprising a dispensing member having a discharge orifice therein, means for feeding powder or the like lying contiguous to the member toward said discharge orifice, and means for opening and closing said orifice automatically.

6. A toilet accessory comprising a rotatable dispensing member having a discharge orifice therein, means on said member for feeding powder or the like lying contiguous to the member toward said discharge orifice, and means for opening and closing said orifice automatically in accordance with the direction of movement of the said member.

7. A toilet accessory comprising a rotatable dispensing member having a discharge orifice therein, a spiral ridge on said member for feeding powder or the like lying contiguous to the member toward said discharge orifice, and means for opening and closing said orifice automatically in accordance with the direction of movement of the said member.

8. A toilet accessory comprising a rotatable dispensing member having a discharge ori-

fice therein, means on said member for feeding powder or the like lying contiguous to the member toward said discharge orifice, and closure hinged flatwise upon said member for 5 opening and closing said orifice automatically in accordance with the direction of movement of the said member.

9. A toilet accessory comprising a rotatable dispensing member having a discharge orifice 10 therein, means on said member for feeding powder or the like lying contiguous to the member toward said discharge orifice, and closure hinged flatwise upon said member with a part of said closure eccentric to the 15 center of rotation of said member and engaged by the powder for opening and closing said orifice automatically in accordance with the direction of movement of the said member.

In testimony whereof, I have hereunto set 20 my hand this 17th day of June, 1931, in the city, county and State of New York.

WILLIAM FRIEDMAN.
